INCINERATOR

Henry Weyenberg and Wayne E. Tice, Holland,
Mich., assignors to Holland Furnace Company,
Holland, Mich., a corporation of Delaware

Application May 4, 1944, Serial No. 534,029

13 Claims. (Cl. 110—18)

1

This invention relates to an incinerator designed primarily for domestic use for consuming household rubbish and garbage.

One object of the invention is to provide a device of this character in which the combustion of the dry rubbish will ordinarily furnish sufficient heat for drying out the wet garbage and like material so that it will eventually be consumed.

Another object of the invention is to provide a structure of this character having a combustion chamber for dry rubbish with a basket or reticulated support for the wet garbage disposed in or adjacent to said combustion chamber and interposed between the chamber and the smoke outlet therefor.

It is also an object of the invention to provide an incinerator which includes a combustion chamber with an air inlet opening in the lower portion of its side wall and with a deflector or baffle adjacent said opening to prevent rubbish in the combustion chamber from blocking the air inlet.

A further object of the invention is to provide an incinerator having a double wall which provides an air jacket around the combustion chamber with air inlet means in the upper portion of the outer wall of the jacket and an air outlet from the jacket to the combustion chamber at the lower portion thereof so that the air must traverse the jacket to reach the combustion chamber and will be preheated in such travel.

More specifically it is an object of the invention to provide an incinerator comprising a combustion chamber which includes a compartment for dry rubbish and a compartment for wet garbage both opening upwardly and provided with a common access cover at the top of the receptacle and in which the garbage compartment has reticulated walls which are interposed between the dry rubbish compartment and the single smoke outlet for the incinerator whereby the products of combustion of the dry rubbish are forced to pass through the wet material in reaching the outlet.

Other objects and advantages of the invention will appear from the following description taken in connection with the drawings in which:

Fig. 1 is a top plan view of the incinerator embodying this invention.

Fig. 2 is a partial side elevation of the incinerator, including only the upper portion, and showing the cover in raised position.

Fig. 3 is a fragmentary horizontal section taken substantially as indicated at line 3—3 on

2

Fig. 5 but including parts of the grill members which extend above the plane of section.

Fig. 4 is a fragmentary horizontal section taken as indicated at line 4—4 on Fig. 5.

Fig. 5 is a vertical section taken as indicated at line 5—5 on Fig. 1.

Fig. 6 is a fragmentary detail section taken at line 6—6 on Fig. 5.

Fig. 7 is a fragmentary detail section taken as indicated at line 7—7 on Fig. 2.

While there is illustrated in the drawings and hereinafter described, a preferred form of the invention, it is contemplated that various modifications may be made by those skilled in the art without departing from the spirit and scope of the appended claims.

The incinerator illustrated in the drawings includes a bottom wall 1 having a marginal flange 2 and an inverted channel 3 which forms an annular rib in its upper surface for spacing its cylindrical outer wall 4 from the cylindrical inner wall 5. The annular air space 6 between these walls is closed at the top by a ring 7 having a marginal flange 8 overlapping the outer wall 4 and a shoulder 9 which positions the inner wall 5. The ring 7 is connected to the bottom 1 by tie rods 10 which thus hold the principal elements of the receptacle in assembled relation.

The space 11 within the cylindrical wall 5 constitutes the combustion chamber while the annular space 6 between the walls 4 and 5 serves as an air passage through which air is led to the combustion chamber. For this purpose the outer wall 4 is provided with a plurality of air inlet ports 12 in its upper portion and, as shown, these inlets are six in number and are disposed in the rear portion of the incinerator. The air entering the ports 12 flows downwardly and around within the annular space 6 to the lower portion thereof at the front of the structure where a delivery opening or port 13 admits it to the combustion chamber 11 within the wall 5. The opening 13 is formed by cutting away a rectangular area of the wall 5, and as a matter of convenience it is located directly opposite a similar opening cut in the outer wall 4 for the clean-out door 14 which is hinged to a frame 15 secured around the opening in the wall 4. The door 14 normally closes the opening in the wall 4, but when it is opened for removing ashes and unburned material from the lower part of the chamber 11, the registering opening 13 provides ready access to said chamber.

The larger portion of the chamber 11 is designed to serve as a compartment for dry rub-

bles and unburned material.

The smaller portion of the chamber 11 is designed to serve as a compartment for wet material.

The chamber 11 is provided with a cover 16 which is hinged to the outer wall 4 and which is

designed to be raised to a position as shown in Fig. 2.

bish which usually consists mainly of paper and readily combustible material and a basket for wet garbage is provided by two curved grills or reticulated walls which are spaced apart and are supported in the combustion chamber 11. The front wall or grill 16 of the garbage compartment is of a forwardly convex curved form approximating a portion of an inverted cone and extending entirely across the chamber 11 at its upper portion but tapering downwardly to a narrow terminal which is carried by a supporting lug 17 riveted to the wall 5 at some distance from the bottom 1, this distance approximating the height of the clean-out door 14 at the opposite side of the chamber 11. The rear wall 18 of the garbage compartment is also in the form of a grill and may be shaped approximately as a portion of a cone of smaller radius than the front wall 16 so as to provide a space between the two grills 16 and 18 to receive the garbage to be dried and consumed in the incinerator. At the lower end the wall 18 tapers almost to a point and rests directly upon the supporting lug 17, being formed with a hook or shoulder 19 for interengagement with a downwardly projecting lug 20 on the lower end surface of the front wall 16, as seen in Fig. 5. An upstanding guard flange 21 of the supporting lug 17 retains the lower end of the grill 18 in position while the interengagement of the hook 19 and lug 20 serve to hold the front wall or grill 16 in position at its lower end. At the upper end the front wall rests against abutment lugs 22 which are cast integral with, and project downwardly from, the top ring 7; and the upper end of the back wall 18 includes lugs 23 from which bolts 24 extend through the top ring 7.

At the rear of the structure the ring 7 includes a segmental portion 7a having an opening 25 which serves as the smoke outlet for the incinerator and which is surrounded by a flange 26 for connection with a smoke pipe indicated in dotted lines at 26a in Fig. 2. Adjacent the straight edge 27 of the area 7a this top casting includes squared openings 28 to receive the rounded hinge lugs 29 of the cover 30 which completes the closure of the upper end of the incinerator and rests upon the inner marginal portion of the ring 7 when in closed position, as shown in Fig. 1. An arm 31 projects from the forward edge of the cover 30 and is provided with a coiled wire handle 32 of the heat radiating type by which the cover may be swung upwardly for access to the dry rubbish and garbage compartments of the structure. A latch or brace arm 33 is pivotally hung from the under side of the cover at 34 in position to ride over and rest upon an upwardly grooved lug 35 which projects inwardly from the ring 7 so that the latch arm 33 serves as a prop to hold the cover in raised position, as shown in Fig. 2, while the waste material is being placed in the incinerator. As shown in Fig. 7, the latch arm 33 is bent with a lateral offset at 33a so that the upper end portion adjacent the pivot at 34 is spaced from the plane of the lower end which engages the grooved lug 35. To release the latch it is only necessary to push the cover 30 upwardly a little beyond the position shown in Fig. 2, thus allowing the latch to swing clear of the lug 35 into a vertically pendant position, as shown in dotted lines; then as the cover is lowered the latch will ride downwardly against the rear face of the lug until the offset 33a passes below the lug, allowing the latch to swing forward into position to ride over the front face of the lug 35 when the cover is again raised. This makes it possi-

ble to raise or lower the cover with one hand and without touching the latch 33 which is likely to be coated with soot as a result of its position in the incinerator during the burning of material therein. The single cover 30 provides access both to the dry rubbish compartment in the chamber 11 and to the garbage compartment formed between the grills 16 and 18. The latch mechanism is the subject of a divisional application Serial No. 607,876, filed July 30, 1945.

When there is sufficient accumulation of material in the incinerator the dry rubbish may be lighted with a match near the top and the cover will be closed, but combustion will be temporarily sustained by air entering the inlet ports 12 and reaching the upper portion of the chamber 11 through a supplemental air port 36 in the front portion of the wall 5. As combustion proceeds, however, the principal portion of the air entering the jacket space 6 through the ports 12 will flow downwardly in the jacket and will enter the chamber 11 through the opening 13, it being understood, of course, that the door 14 is normally kept closed. To prevent the opening 13 from becoming clogged with refuse and rubbish in the chamber 11 a baffle or deflector plate 37 of the form shown in dotted outline in Fig. 4 extends from the inner surface of the wall 5 as a hood over the space adjacent the door 14, as indicated in Fig. 5. It will be evident that, if desired, the door 14 may be momentarily opened and a match may be applied to the material in the lower portion of the chamber 11.

As combustion proceeds and the smoke and hot gases pass through the openings of the grills 16 and 18 and through the wet garbage held between them so as to escape through the smoke outlet 25, and the air which is drawn in through the ports 12 is rapidly heated as it flows downwardly through the annular jacket space 6 and around the wall 5 of the combustion chamber 11, this air thus enters the lower portion of the chamber 11 through the opening 13 at a fairly high temperature, which may reach 600 or 700 degrees F. Any excess of this heated air which is not required to support combustion flows with the products of combustion through the grills 16 and 18 and assists in the drying of the wet material until this material is in condition to burn also. To insure this result in the event that the garbage compartment is not entirely filled, the upper portion of the wall 18 is formed as shown at 38, without openings, so as to serve as a baffle adjacent the smoke outlet 25 which prevents the products of combustion in the upper portion of the chamber 11 from reaching the smoke outlet without first passing through the reticulated portion of the wall 18 and through the wet garbage held in this lower portion of the basket.

For simplicity and economy of construction the incinerator is made in a generally cylindrical form requiring no special bending or forming of the side walls 4 and 5; and it will be noted that the assembly of the parts thus becomes an extremely simple matter, which consists mainly of the placing of the side walls between the bottom wall 1 and the top ring 7 and securing the tie bolts 10 which hold these parts together. The hinge lugs 29 of the cover are not fastened in place but merely fit loosely into the openings 28 into which they swing when the cover is raised; the rear grill 18 of the garbage basket is readily placed in position and secured by the two bolts 24, 24, while the front grill 16 is simply lodged in its position of use and can be quickly removed,

if desired. It is found unnecessary to provide a bottom grate in a structure of this character, and practically all material burns to a fine light ash which can be easily removed through the clean-out door 14.

We claim as our invention:

1. In an incinerator, an outer wall, an inner wall spaced therefrom and defining a combustion chamber, said outer wall having air inlet means in its upper portion only, the inner wall having a principal air inlet means in its lower portion which constitutes the only means of substantial capacity for admitting air from the space between said walls to the combustion chamber, a single smoke outlet for said chamber and an upwardly open basket structure in said chamber dividing it into a compartment for dry rubbish and a compartment for wet garbage with the garbage compartment interposed in the path of products of combustion moving from the rubbish compartment to said smoke outlet.

2. An incinerator comprising an outer wall, an inner wall spaced therefrom said inner wall defining a combustion chamber, said outer wall having air inlet means in its upper portion only, the inner wall having air delivery means in its lower portion constituting the only means of substantial capacity for admitting air from the space between said walls to the combustion chamber, said chamber having its only outlet for smoke and other products of combustion leading from the upper portion of the chamber, and a basket structure for wet garbage disposed within said chamber adjacent and below said outlet.

3. In an incinerator as defined in claim 2, said inner wall having a single auxiliary port of limited capacity in its upper portion for delivering air to initiate combustion in the upper part of said combustion chamber.

4. In an incinerator as defined in claim 2, an imperforate clean-out door installed in the outer wall directly opposite said air delivery means of the inner wall, said means comprising an opening in the inner wall at least as large as said door, whereby said opening affords access to the combustion chamber through the clean-out door.

5. In an incinerator, means defining a combustion chamber having an air inlet in its lower portion and a single outlet for the products of combustion leading from the top of the chamber together with an upwardly open basket structure in said chamber dividing it into a compartment for dry rubbish and a compartment for wet garbage, said basket including a wall extending downwardly from the top of the chamber and across it into engagement with the side walls confining a space immediately below the smoke outlet, and a reticulated wall spaced from said first mentioned wall and also extending downwardly from the top of the chamber to form the garbage compartment, the lower portion of said first mentioned wall being also reticulated to permit air and the products of combustion to flow through the garbage in passing to the smoke outlet, but the upper portion of said wall serving as a baffle to prevent direct flow of smoke and gases to said outlet through the upper part of the basket.

6. In an incinerator, means defining a combustion chamber, a separate top member therefor, said combustion chamber having an air inlet in its lower portion and a single outlet for the products of combustion leading from the top of the chamber together with an upwardly open basket structure in said chamber dividing it into

a compartment for dry rubbish and a compartment for wet garbage, said basket structure including a pair of reticulated walls spaced apart and both extending downwardly from the top of the chamber and across it adjacent the side walls, a supporting lug on the inner face of the combustion chamber wall, both basket walls resting upon said lug and being upwardly removable therefrom, and abutment lugs extending downwardly from said separate top of the combustion chamber structure, one of said basket walls being inclined upwardly from said supporting lug and away from the wall of the combustion chamber with its upper end portions resting against said abutment lugs, the top member having an opening directly over said last-mentioned basket wall, whereby the basket wall may be inserted and removed through said opening, and a cover for said opening.

7. In the combination defined in claim 6, said supporting lug having an upwardly projecting guard flange by which the lower ends of the basket walls are retained in place on said lug.

8. In an incinerator, means defining a combustion chamber having an air inlet in its lower portion and a single outlet for the products of combustion leading from the top of the chamber together with an upwardly open basket structure in said chamber dividing it into a compartment for dry rubbish and a compartment for wet garbage, said basket structure including a pair of reticulated walls spaced apart and both extending downwardly from the top of the chamber and across it adjacent the side walls, the combustion chamber defining means including a top ring with a fixed segmental portion containing the smoke outlet and a cover hinged to said portion, a supporting lug on the lower portion of the face of the combustion chamber wall, one of said reticulated walls of the basket structure resting upon said lug and being upwardly removable therefrom with means connecting the upper portion of said wall with the segmental part of the top ring and adjacent the hinged cover, the other wall of the basket structure extending upwardly in the chamber from said supporting lug and under the hinged cover whereby said cover affords access to the basket and the basket is interposed between the dry rubbish compartment and the smoke outlet.

9. An incinerator comprising an outer wall and an inner wall with an annular space between them, said inner wall defining a combustion chamber, a top member closing said space, said outer wall having an air inlet to said space in its upper portion only, said inner wall having an air delivery port in its lower portion admitting air from said space to said combustion chamber, the top member including a fixed portion which extends over a part of the combustion chamber with a smoke outlet in said portion constituting the only outlet for products of combustion, and a single hinged cover adjoining said fixed portion and extending over the remainder of the combustion chamber, together with an upwardly open reticulated basket structure disposed within said chamber, dividing the chamber into a compartment for wet garbage and a compartment for dry rubbish, said cover affording access simultaneously to both compartments.

10. In an incinerator, means defining a combustion chamber with a reticulated partition laterally dividing said chamber into a compartment for dry rubbish and a compartment for wet garbage, said chamber having an inlet for air in its

lower portion and having its only outlet for smoke and other products of combustion located in its upper portion, the garbage compartment being interposed in the path of products of combustion moving from said dry rubbish compartment to said outlet, said partition being inclined with relation to the vertical with a larger space therewithin at the top than at the bottom, all of the products of combustion passing through the wet garbage compartment and therefrom directly into the smoke outlet.

11. In an incinerator as claimed in claim 10, in which said reticulated partition extends downwardly substantially from the top wall of the chamber and terminates at a substantial distance above the bottom wall thereof and being of conical curvature on its inner portion.

12. In an incinerator, means defining a combustion chamber having an air inlet in its lower portion and having its only outlet for the products of combustion leading from the top of the chamber, and a reticulated inclined partition enclosing the space in said chamber adjacent said outlet and dividing the chamber into a dry rubbish compartment and a wet garbage compartment laterally spaced from each other whereby products of combustion formed in said chamber outside said space are required to pass through said partition to reach the outlet, said outlet being on the wet garbage side of the inclined partition.

13. An incinerator comprising a bottom wall, a top, and connecting wall means therebetween, all cooperating to form a combustion chamber with an inlet for air in the lower portion of said

5 chamber and a single outlet for the products of combustion in the upper portion of said chamber, reticulated partition means dividing said combustion chamber into a compartment for wet garbage and a compartment for dry rubbish, said top including a single hinge cover opening upwardly and affording access simultaneously to both compartments at the same side of the axis of the hinges of said covering, said partition on its inner side being of conical curvature diminishing in size downwardly.
